UNITED STATES PATENT OFFICE.

ROBERT JOHNSON AND JOHN F. BUERKEL, OF BOSTON, MASS., ASSIGNEES
TO THE JOHNSON RAILWAY HEATER COMPANY, OF SAME PLACE.

HEATER.

SPECIFICATION forming part of Letters Patent No. 279,486, dated June 12, 1883.

Application filed September 28, 1882. (No model.)

To all whom it may concern:

Be it known that we, ROBERT JOHNSON and JOHN F. BUERKEL, of Boston, Suffolk county, Massachusetts, have invented Improvements in Heaters, of which the following is the specification.

Our invention is an improvement in that class of railway-car heaters in which the water, glycerine, or any of the usual fluids is circulated without pressure or at a nominal pressure, as in the heater patented to Jonathan Johnson, February 7, 1882; and our invention has for its object to secure a rapid circulation and facilitate the speedy heating of the car after the fire is kindled, while permitting the automatic feeding from a large tank to supply any loss from evaporation or leakage.

The drawing represents in vertical transverse section a passenger-car with one of our improved heaters, similar in many respects to that shown in the aforesaid Letters Patent.

A is the heater or stove, of any suitable form and construction.

E is the supply-chamber, and C the circulating-chamber, both, in this instance, contained in one tank, F.

a is the water-gage on either tank or chamber.

D is the condenser, communicating with the chamber C through a pipe, b.

In the before-named patented heater the water circulated from the coils and stove through the chamber C, and would become rapidly heated after kindling the fire; but injury was liable to result from the evaporation of the small body of water in the chamber C should the attendant neglect to turn on in time a proper supply from the chamber E. This injury could be prevented by circulating the water through the larger chamber; but the time requisite to heat so large a body of fluid

would delay the heating of the car. To avoid both of these objections, we circulate the water from the stove and the coils through the chamber C, the pipe e from the furnace or 45 stove, and pipe f from the coils leading to said chamber, and we put the chamber E into separate communication with the heating-pipes by means of a pipe, i. The water will, in heating, thus circulate through the limited chamber C, and the entire body will speedily reach the required temperature; but any loss from evaporation or leakage will be automatically supplied from the chamber E, so that the water in both chambers is maintained at the same 55 level. We thus secure the advantage of a large body of water in constant communication with the pipes, and the advantage resulting from circulating through a small chamber and heating only a small body of water where 60 the fire is started.

We claim—

The combination, in a hot-water heating apparatus, of a limited circulating-chamber arranged outside the heater, open to the external atmosphere, and communicating both with the water-pipes in the stove and with the radiating pipes or coils, and an independent larger supply-chamber communicating with the heating or circulating pipes, whereby the 70 water is circulated through the coils and small chamber without pressure and all loss from evaporation supplied from the larger chamber, as set forth.

In testimony whereof we have signed our 75 names to this specification in the presence of two subscribing witnesses.

ROBERT JOHNSON,
JOHN F. BUERKEL.
